CLAIM

The ornamental design for a light bulb as shown and described.

DESCRIPTION

FIG. 1 is a front perspective view of the light bulb showing our new design;

FIG. 2 is a front view of the light bulb;

FIG. 3 is a rear view of the light bulb;

FIG. 4 is a left side view of the light bulb;

FIG. 5 is a right side view of the light bulb;

FIG. 6 is a top plan view of the light bulb; and,

FIG. 7 is a bottom plan view of the light bulb.

In the drawings, the broken lines illustrate portions of the light bulb in which the design is embodied and form no part of the claimed design.

1 Claim, 6 Drawing Sheets
